GUSSET FOR ATTACHING LEGS TO TABLES

Irving Rubin, 800 Newton St., Brookline, Mass.

Filed Apr. 10, 1963, Ser. No. 74,384

Term of patent 14 years

(Cl. D54—1)

FIG. 1

FIG. 2

FIG. 3

FIG. 4

FIG. 1 is an inverted perspective of a gusset for attaching legs to tables showing my new design;

FIG. 2 is a perspective view thereof taken from the side opposite that of FIG. 1;

FIG. 3 is a bottom plan view, and

FIG. 4 is a top plan view.

I claim:

The ornamental design for a gusset for attaching legs to tables, substantially as shown.
